BEDSTEAD

Sander Baker and Nick Stefano, Cleveland, Ohio; said
Stefano assignor to said Baker

Application March 8, 1956, Serial No. 40,519

Term of patent 14 years

(Cl. D5—4)

Fig. 1

Fig. 2

Fig. 1 is a perspective view of a bedstead embodying our new design; and

Fig. 2 is a similar perspective view thereof with one of the hinged guard elements in folded position.

The dominant features of the design reside in the portions disclosed in full lines.

We claim:

The ornamental design for a bedstead, substantially as shown and described.
